Higdon & Higdon

UNITED STATES PATENT OFFICE.

JOCHAN F. RAUHUT, OF ST. LOUIS, MISSOURI, ASSIGNOR OF ONE-HALF TO
WILLIAM HINZE, OF SAME PLACE.

VELOCIPED.

SPECIFICATION forming part of Letters Patent No. 433,962, dated August 12, 1890.

Application filed June 6, 1890. Serial No. 354,451. (No model.)

To all whom it may concern:

Be it known that I, JOCHAN F. RAUHUT, a subject of the Emperor of Germany, and a resident of the city of St. Louis, in the State 5 of Missouri, have invented certain new and useful Improvements in Velocipedes, of which the following is a full, clear, and exact description, reference being had to the accompanying drawings, forming a part hereof.

10 My invention has for its object to provide certain new and useful improvements in velocipede-wagons; and it consists in the novel combination and arrangement of parts, all of which will be hereinafter more fully described, 15 and designated in the claims.

In the drawings, Figure 1 is a longitudinal sectional view of my invention, taken on the line *xx* of Fig. 2. Fig. 2 is a bottom plan view of my invention. Fig. 3 is a top plan 20 view of the steering-handle and its attachment. Fig. 4 is a perspective view of the spring-lock, and Fig. 5 is a perspective view of the collar used in connection with the spring-lock.

25 Referring to the drawings, 1 represents the body of the wagon having the usual running-gear and wheels 2 applied thereto.

30 3 represents the rear axle, which is provided with three sprocket-wheels 4, 5, and 6, each 30 of which is of a different size, for the purpose of increasing or diminishing the speed of the wagon, as may be desired.

35 11 represents a dependent bracket secured to the under surface of the floor of the wagon, 35 said bracket having two bearings *ee* for the rotating shaft 12, which shaft forms the intermediate connection for the power-chains.

To the shaft 12 are keyed sprocket-wheels 8, 9, and 10, which correspond in size to the 40 sprocket-wheels 4, 5, and 6, and in a direct alignment with the same, but taper in an opposite direction.

45 7 represents one of the drive-chains running over a pair of the sprocket-wheels 5 and 9, which are of the same size; but said chain is interchangeable and can be applied to the remaining sprocket-wheels, which will increase or diminish the speed, as may be desired.

50 13 represents a comparatively large sprocket-wheel keyed or otherwise fastened to the

free end of the horizontal shaft 12, over which a second drive-chain 14 passes.

15 represents a sprocket-wheel located above the floor of the vehicle and is provided 55 with a suitable handle 16, by means of which the same is turned.

20 represents a suitable bearing for the sprocket-wheel 15, which bearing is fastened to the upper surface of the floor and located 60 in easy reach of the driver. The drive-chain 14 passes over the sprocket-wheels 13 and 15, forming a driving connection, and which in its revolution operates the shaft 12.

17 represents a crank-arm secured to the 65 free end of the shaft 12, said crank-arm being bolted or otherwise secured to a pitman 18, which forms a connection with a hand-lever located within the body of the vehicle.

19 represents the hand-lever, to one end of 70 which is connected the pitman 18, and its opposite or free end formed into a suitable handle for the convenience of the operator.

21 represents a bearing secured to the upper surface of the floor of the vehicle, to which 75 the hand-lever 19 is movably secured and supported thereby.

29 represents a friction-pulley, which is fastened to the upper surface of the floor of the wagon or vehicle and bears against the drive-chain 80 14.

22 represents a vertical steering-rod, which is located in the forward part of the vehicle and in direct communication with the forward wheels, said rod working loosely through one 85 of the projecting arms 23 of the fifth-wheel, and having a right-angled extension *a*, leading to and connected to a projecting arm 24, rigidly secured to the forward axle. To the upper end of the steering-rod is secured a lever or handle 25, by means of which the rod 22 is turned, when desired.

26 is a collar which encircles the vertical shaft, and is located upon the same near the floor of the vehicle, said collar having a notch 95 or recess *b*, for receiving the spring-catch 27, which prevents the vertical rod 22 from turning when in a locked position.

27 represents the spring-catch, which is secured to lugs or bearings *cc*, fastened to the 100 floor of the vehicle and capable of movement between the same. The spring-catch 27 has

a downwardly-projecting lug *d*, which is adapted to receive the recess *b* and lock the upright rod in a rigid position, as shown in Fig. 3. A coil-spring 28 is secured to the 5 floor of the vehicle and bears against the under surface of the latch 27, which spring holds the said latch in a locked position.

The spring-latch is adapted to hold the forward axle in a horizontal position and thus 10 relieve the operator from strain that would be otherwise imposed upon him when the vehicle is running in a straight line. This motor is intended to be driven entirely by hand, either by the lever 19 or by the sprocket-wheel 15, both of which in their turn operate the sprocket-wheel 13 and shaft 12, imparting motion to the wheels 8, 9, and 10, which last-named wheels in their turn revolve the wheels 4, 5, and 6 by means of the drive-chain 7, 20 causing the axle 3 to be revolved and thus the driving-power is established. The hand-lever 19 is only intended to be used should the sprocket-wheel 15 or any of its parts become disabled, thus avoiding the usual breakdowns 25 common to this class of velocipedes.

Having fully described my invention, what I claim is—

1. In a velocipede, the combination of the steering-rod 22, having the arm *a* and handle 25, the collar 26, secured to the said rod and 30 provided with a notch *b*, the spring-catch 27, having a downwardly-projecting lug *d*, and a coil-spring 28, bearing against the under surface of the said latch, substantially as described.

2. In a velocipede-wagon, the combination of the axle 3, sprocket-wheels 4, 5, and 6, keyed thereto, the bracket 11, carrying shaft 12, the sprocket-wheels 8, 9, and 10, secured to the said shaft, the drive-chain 7, forming 40 a connection between the two sets of sprocket-wheels, the crank-arm 17, fastened to the shaft 12, the hand-lever 19, located above the floor of the vehicle and fastened to the lug or bearing 21, and the pitman 18, connecting the said 45 hand-lever with the crank-arm, substantially as described.

In testimony whereof I affix my signature in presence of two witnesses.

JOCHAN F. RAUHUT.
